Primary Examiner — Charles D Hanson(74) *Attorney, Agent, or Firm* — Culhane Meadows, PLLC(57) **CLAIM**

The ornamental design for a caddy, as shown and described.

DESCRIPTION

FIG. 1 is a front perspective view of a caddy, in accordance with our new design.

FIG. 2 is a bottom perspective view of the caddy, in accordance with our new design.

FIG. 3 is a right-side view of the caddy, in accordance with our new design.

FIG. 4 is a left-side view of the caddy, in accordance with our new design.

FIG. 5 is a left end view of the caddy, in accordance with our new design.

FIG. 6 is a right end view of the caddy, in accordance with our new design.

FIG. 7 is a top view of the caddy, in accordance with our new design; and,

FIG. 8 is a bottom view of the caddy, in accordance with our new design.

In the drawings, the broken lines indicate portions of the article not claimed or the unclaimed environment and form no part of the claimed design.

1 Claim, 8 Drawing Sheets(56)
